WEATHERSTRIP AND FLASHING STRUCTURES

Walter E. Horrocks, Lakewood, Ohio

Application August 24, 1956, Serial No. 606,144

8 Claims. (Cl. 20—69)

2

Fig. 5 is a sectional view through a door jamb and a door stile having L shaped and Z shaped weatherstrips applied thereto, and being secured with the ribs bedded in an angular seated arrangement.

5 Fig. 6 is a sectional view showing a channel structure provided with an oblique rib 15, which is to be serrated along its margin as indicated at 16 in the Fig. 10.

Fig. 7 is a sectional view showing an F shaped weatherstrip provided with an oblique penetrating rib 15, which is to be serrated along its margin as is indicated at 16 in the Fig. 10.

10 Fig. 8 is a sectional view showing an L shaped weatherstrip structure provided with an oblique rib 15, that is covered with its face as indicated in the Fig. 11.

15 Fig. 9 is a sectional view showing a Z shaped weatherstrip provided with an oblique rib that is covered by its face as indicated in the Fig. 11.

Fig. 10 is a partial perspective enlarged view illustrating an obliquely inclined piercing rib provided with a series 20 of saw teeth, or serrated piercing means.

Fig. 11 is a partial perspective enlarged view illustrating an obliquely inclined piercing rib provided with a series of saw teeth, or serrated piercing means which are covered by the face portion of the weatherstrip or flashing structure.

25 Fig. 12 is a partial perspective enlarged view illustrating an obliquely inclined piercing rib provided with a chamfered piercing edge, and also a series of serrated piercing means arranged along the margin of the chamfered edge, with the rib and its piercing means being covered by the face portion of the weatherstrip or flashing structures.

30 In the accompanying drawings forming a part of this application I have illustrated the improvements as applied to window framing, door framing, building sheathing elements and the weatherstripping of weather-board siding, such as is universally used in the building arts and termed as flashing, although the invention is not to be restricted to these specified applications.

35 The Figures 1 and 2 illustrate the application of the invention as it is applied to an L shaped structure, with the slanting piercing rib 15 projecting obliquely from one leg of the L shaped structure which is initially positioned

40 on the top side of the element 19 to which it is to be applied as shown in the Fig. 1, then as the obliquely disposed slanting piercing rib 15 is hammered downwardly into the element 19, the serrated marginal edge of the piercing rib 15 bites into the element 19 and moves the

45 face surface of the structure obliquely towards the left substantially as shown in the Fig. 2 which embeds the obliquely disposed slanting rib 15 into the element 19 in an undercut seated position in which the obliquely shifting line of travel of the L shaped structure is indicated

50 by the dotted line 20 substantially as is indicated between the Figures 1 and 2. It is to be noted that the slanting piercing rib 15 being embedded in an undercut seated position in the element 19 is immune from easy extraction from the element 19, such as when a vertical

55 pull is applied to the exposed upstanding leg of the L shaped structure, and the piercing edge 16 of the slanting rib 15 is also prevented from curling outwardly beyond the end of the L shaped structure.

Fig. 3 and Fig. 4 illustrate the invention as applied to 60 flashing around the framing elements 21 of a double hung window structure, showing the sheathing S and weather-board W, which is generally applied as shown in the Fig. 3, with the interior plaster finish indicated as at P. The L-shaped flashing structure is initially positioned as shown in the Fig. 4, having the upstanding leg of the L-shaped structure bent slightly in a manner to initially position the top edge of the L-shaped structure in close

My present invention relates to new and useful improvements in Weatherstrip and Flashing Structures embodying additional characteristics and advantages over the structures disclosed in my co-pending application titled Weatherstripping, Serial No. 472,294, filed December 1, 1954, and my co-pending application titled Weatherstripping Structures, Serial No. 568,301, filed February 28, 1956, with the additional characteristics adapted for incorporating into various articles of manufacture.

In utilizing the structures disclosed in the aforesaid applications, the piercing ribs being formed at an angle of ninety degrees, does not disclose the additional uses and advantages that are inherent in the present disclosed structures as when the piercing ribs are arranged to project in an oblique direction from the back sides of the structures in a manner that permits of the structures to shift horizontally so that the piercing ribs will become embedded in an undercut seating arrangement in such a manner that will better hold and secure the structures to the elements to which they are applied, as is herewith illustrated and described for utilizing the invention for different applications.

An important object of the invention is to provide a weatherstrip or flashing element providing a serrated penetrating rib arranged to be driven obliquely into wooden elements and the like and be embedded in an angular seated position therein.

Another object is to provide a weatherstrip or flashing element that can be embedded in an angular undercut seated position.

Another object is to provide a weatherstrip or flashing element having a serrated penetrating rib that will provide an undercut seal.

Another object is to provide a weatherstrip or flashing element providing an improved anchorage means.

Still another object is to provide a weatherstrip or flashing element that can shift horizontally when its penetrating means is driven to its seating position into wood elements and the like.

Other objects and advantages of the invention will be apparent when analysing the drawings in conjunction with the accompanying specifications.

The Fig. 1 is a sectional view showing an L shaped element provided with an obliquely disposed penetrating rib initially arranged to be driven into a wood element in a manner to be seated in an undercut seated position as shown in Fig. 2, 3, and 5, inclusive.

Fig. 2 is a sectional view showing the L shaped structure after the piercing means and rib have been driven into the wood element.

Fig. 3 is a sectional view through a head member of a double hung window frame showing an L shaped flashing embedded in the window frame.

Fig. 4 is a sectional view through the head member of a double hung window frame showing the initial position of the L shaped flashing before being driven into the window frame.

abutting contact against the sheathing *S* which provides for driving the oblique slanting piercing rib *15* downwardly and obliquely into the window frame *21* in a manner so that the upstanding leg of the L-shaped weatherstrip will be bent back in a manner to hug up against the sheathing *S* substantially as shown in the Fig. 3, after which the weather-board *W* is applied over the flashing and nailed to the sheathing *S*. It is to be noted and it is intended to utilize the flashing elements around the outer sides of door framing members in substantially the same arrangement as shown and described for flashing around a double hung window structure, and it is intended to use the obliquely inclined ribs *15* in a manner as shown the Figures 1, 3, 4, 5, or 10, to provide the structure with means so as to be seated in an undercut seated position.

Fig. 5 illustrates the invention as applied to weatherstripping a door jamb *22* and a door stile *23* assembly in which the slanting piercing rib *15* is covered over by the face portion of the weatherstripping members, utilizing the L-shaped and the Z-shaped structures that are disclosed in my co-pending application Serial No. 568,301, filed February 28, 1956. In the application of the weatherstripping structures to the present illustrated assembly, the L-shaped structure is initially positioned on the face of the stile *23* so that the upstanding leg of the L-shaped structure lays against the face of the door jamb *22*, then the obliquely inclined slanting rib *15* is driven downwardly and obliquely into the element *23* and the upstanding leg of the L-shaped structure will be shifted away from the face of the door jamb *22* so as to allow of a clearance space between the back side of the leg of the weatherstrip and the door jamb *22* such as when the door stile *23* is swung away from, or closed against the rabbet provided in the door jamb *22*. The Z-shaped structure is then initially positioned on the face of the jamb *22* so that the free end of the Z-shaped structure lays against the face of the L-shaped structure, then as the obliquely inclined slanting rib *15* is driven downwardly it will move obliquely into the element *22* and the free end of the Z-shaped structure will be shifted away from contact with the face of the L-shaped structure so as to allow of a clearance space between the face of the L-shaped structure sufficient to provide of a working clearance, and subsequent overlapping coats of paint which may be subsequently applied, without the said structures becoming frictionally bound.

It is to be noted that it is intended to use any of the disclosed obliquely inclined slanting ribs together with any one of the figures disclosed in order to provide a piercing means that is suitable for various different specific requirements, and it is intended to join the invention to various other shapes that lend them to useful purposes, such as for illustration the figures shown 6, 7, 8, and 9 inclusive which shapes are suitable to provide such articles of manufacture as, shelving cleats or brackets, and runways to support sliding drawers and similar

articles. The uses described can be better visualized by viewing the drawing positioned in a horizontal position which shows a channel shape provided with the obliquely inclined slanting rib *15*, and the F-shaped structure provided with an obliquely inclined slanting rib in which both of the structures provide of a slideable runway in which shelves or drawers are allowed to slide, without tipping either up or down, and the Figures 8 and 9 illustrate structures having a ledge or flange that is suitable for use as shelf brackets, with the structures being provided with obliquely inclined slanting ribs which when driven into elements *19* similar to such as is shown in the Fig. 2 and Fig. 5 which provides an imbedded securing means that eliminates the use of nails or screws to secure the elements in a permanent obliquely seated undercut position.

It is to be understood that the forms of my invention, herewith shown and described, is to be taken as preferred examples of same, and that various changes in shape, size and arrangement of parts may be resorted to, and I reserve the right to the use of different materials without departing from the spirit or concept of my invention, or the scope of the subjoined claims.

Having thus described my invention as to what is new I claim:

1. A weatherstrip structure comprising a body portion having a face side and a back side, said body portion having a flange rebent upon the back side and extending between the ends of the body portion, an upstanding rib formed at the end of said flange and extending away from said body portion, the edge of said rib being serrated along its margin.
2. A weatherstrip as described in claim 1, in which the body portion has an L-shape cross section.
3. A weatherstrip as described in claim 1, in which the body portion has a Z-shape cross section.
4. A weatherstrip as described in claim 1, in which the body portion has an F-shape cross section.
5. A weatherstrip as described in claim 1, in which the upstanding rib is perpendicular to the body portion.
6. A weatherstrip as described in claim 5, in which the body portion has an L-shape cross section.
7. A weatherstrip as described in claim 5, in which the body portion has a Z-shape cross section.
8. A weatherstrip as described in claim 5, in which the body portion has an F-shape cross section.
